UNITED STATES PATENT OFFICE.

JAMES A. BISHOP, OF DENVER, COLORADO.

PROCESS FOR DESULPHURING UNSATURATE AND WASTE OILS AND THEIR CONVER- SION INTO SATURATE HYDROCARBONS.

Application filed April 9, 1923. Serial No. 830,940.

This invention has to do with an improved process for the distillation of oils and oil bearing materials, and also has to do with an improved process for the removal 5 of sulphur and sulphurous materials from the oils and distillates. One feature of the invention has to do with an improved distillation process which is particularly well adapted for the distillation of oil bearing 10 sands and similar mineral substances such as oil shale and the like. Another feature of the invention has to do with a distillation process which is particularly well adapted for the recovery of an increased, or 15 exceptionally large, yield of gasoline and other similar distillates, with a minimum amount of production of light paraffine and olefin gases by cracking.

In order that the features of the present 20 invention may be better understood and their significance more readily appreciated, I will state first that the degree of heat applied to a composite of oils or to a solid having a potential oil value determines to 25 a large degree the molecular forms of the distillates. An oil bearing shale, when finely pulverized, is also as susceptible to the action of heat as a composite of oils, and the present process may be applied either to oils 30 or to pulverized oil bearing solids such as shale. In either case there will be an increase in the production of the lighter hydrocarbon oils as derivatives from heavy petroleum unsaturates, and asphaltic base oils, 35 such as are often found in shale, sand and peat.

The gas forming stages in distillation processes are two in number. First, at low temperature when the charge is raised gradually to the distilling temperature, the heat 40 is sufficient only to tear off light molecules from the charge and lift them in opposition to the super-posed vapor pressure. Second, the second gas forming, or high temperature stage occurs when the heat becomes sufficiently intense to crack the heavy paraffines by tearing off the terminal carbon atoms of the heavy molecules. These terminal atoms then unite to form the light 45 ethane gas, a paraffine, or saturate, I, therefore, adopt the plan of feeding the charge, either pulverized shale or oil, slowly into the distilling mass, which is already at the distilling temperature. For the prevail-

ing commercial oils this temperature runs 55 from 400 to 450 degrees centigrade. It is evident that oil or pulverized shale plunged suddenly, in small quantities, into a charge maintained at this temperature, the increment charge is brought instantly to the 60 temperature of the main charge. We know that a pure gasoline may be raised to 600° C. before the cracking process converts it into light paraffine and olefin gases. Hence a heat of 400° to 450° C. avoids the low temperature 65 gas forming stage, while the high gas forming or cracking stage has not been reached. Pulverized solids, as shale for example, can be instantly brought to this desired temperature in a preheater in which 70 small volumes of the charge can be easily controlled. The charge in the preheater may be dropped into a dry furnace heat, or a high boiling fluid previously heated to the desired temperature or superheated steam 75 may be injected into the preheated charge. After the preheating the increment charge may be fed into the general retort charge. In case the process is being applied to the distillation of oil, said oil may be fed slowly but directly into the still charge, but 80 preferably forced into the oil below the surface, where it is instantly incorporated into the hot charge. Since this part of the process is principally made up of manipulations, any device may be employed which 85 meets the suggested requirements.

The presence of sulphur in the oil or derivatives is extremely detrimental from different standpoints. The sulphur generally gives to the oil a detrimental smell or odor, and when the oil is burned, the sulphur present passes off as SO_2 or sulphur dioxide. This sulphur dioxide immediately associates itself with any moisture present 90 for the formation of sulphurous acid, H_2SO_3 , and the sulphurous acid in turn frequently undergoes changes by which it is converted into sulphuric acid H_2SO_4 . Either the sulphurous or sulphuric acid will 95 react with boilers or flues or other metallic objects with serious corrosion and deterioration.

In order to eliminate the sulphur from the oil and its derivatives, I make use of 100 the extremely violent chemical affinity of nascent hydrogen for the sulphur present in the oil and which is to be eliminated.

The nascent hydrogen combines with the sulphur to form H_2S or hydrogen sulphide. This is a gas.

Ordinary or quiescent hydrogen does not possess a sufficient affinity for the sulphur in the oils to combine with it for the purpose of removing it therefrom, and it, therefore, becomes necessary to provide a process and arrangement for generating the nascent hydrogen on the spot and in immediate contact with the oil and its sulphur content.

Nascent hydrogen may be produced in quantities by bringing carbon monoxide, CO , into contact with steam, H_2O , at a temperature of 400° to 500° C. The following reaction then takes place: $CO + H_2O = CO_2 + 2H$. The instant that the carbon monoxide gas and water are brought into contact at the proper temperature they will react according to the above equation and generate the hydrogen. This hydrogen is nascent at the instant of generation, but immediately afterwards becomes quiescent. In order to secure the beneficial action of the hydrogen on the sulphur it therefore becomes necessary to bring about this reaction in the immediate presence of the oil containing the sulphur. I, therefore, contemplate the generation of the carbon monoxide and the steam in separate places, and contemplate bringing them together under the desired temperature at the point where the oil to be acted upon is located. This contemplates bringing the carbon monoxide and the steam together at a temperature of 400° – 500° C. at the point where the oil or shale is located.

The carbon monoxide may be generated in any suitable manner, but conveniently as producer gas in a gas producer. If this gas producer is equipped for both air and steam blow, the air blow should produce a gas having substantially a 48% content of carbon monoxide and a substantially equal volume of atmospheric nitrogen. The steam blow should produce a gas which approximates 48% carbon monoxide and 48% hydrogen in place of atmospheric nitrogen. In either case, however, the carbon monoxide gas will be produced at high temperature, so that it will not be necessary to afterwards heat it to the desired temperature for use in the production of the nascent hydrogen in contact with the oil.

The introduction of the hot carbon monoxide and steam individually into the shale or the body of the oil being treated may be done in any convenient manner, as for example by the use of rabbles such as are disclosed in the Bishop Patent No. 1,166,175. In such case a rabble should be provided with passages for the independent introduction of the carbon monoxide and the steam, which passages will be brought close together at their discharge points, so that

the reaction of the carbon monoxide and steam will take place at the instant these gases reach the material being acted upon.

The introduction of nascent hydrogen into contact with the oil or oil bearing material will produce another action besides combination with the sulphur; any deficiency of hydrogen within the oil is made up by the nascent hydrogen, since unsaturated hydrocarbons cannot exist as such when in contact with nascent hydrogen, although the nascent hydrogen is inert as far as the hydrocarbons are concerned when the latter are fully saturated. The action by which the nascent hydrogen raises the unsaturates to the condition of saturates, whence they originated, may be better visualized by considering the hypothetical molecule of amylene oil. The molecule of amylene oil may be represented as five four sided polygons each representing an atom of carbon. The adjacent corners of three pairs of these polygons come together, leaving ten exposed points representing ten atoms of hydrogen, and the second and third polygons are brought together by a double linkage. Upon saturating this molecule of amylene oil with hydrogen, the double linkage is broken to expose two additional points between the second and third carbon atoms, thus representing two additional atoms of hydrogen. Quiescent hydrogen does not have sufficient affinity for the carbon to open up the chain between the second and third carbon atoms, and consequently, cannot saturate the amylene oil. Nascent hydrogen, however, does possess sufficient affinity for the carbon to break open this linkage and thus saturate the amylene oil with hydrogen and produce rhigolene oil which is a saturated paraffine.

Therefore, by the introduction of nascent hydrogen into the body of the oil or into contact with the oil bearing material as is done in my process also results in the conversion of the unsaturates into 100% saturates with corresponding increase in the commercial value of hydrocarbon oils of saturated purity.

The nascent hydrogen also has a very large affinity for nitrogen, and most mineral oils contain more or less nitrogen in their body. This will combine with the nascent hydrogen to produce NH_3 or ammonia, which is a valuable by product of many distillation processes.

After producing the H_2S in the body of the material by the action of nascent hydrogen on the sulphur, it is desirable to eliminate the same by a precipitation process instead of allowing the gas to remain in the oil or pass off as such. The CO_2 gas generated during the process of liberating the nascent hydrogen is also an objectionable material within the body undergoing treat-

ment. Both the CO_2 and H_2S may be absorbed by lime, either in the quick or slaked condition, as CaO or $\text{Ca}(\text{OH})_2$, with tremendous avidity. The introduction of a small quantity of lime into either a solid or liquid oil charge undergoing treatment will eliminate both the CO_2 and the H_2S compounds and produce solid calcium compound during the process, which calcium may be easily eliminated by precipitation or otherwise.

In case any small trace of sulphur should be left in the material, it may be readily removed from the vapors by passing them through a screen, scrubber, or other device on which a spray of lead acetate solution is made to flow.

Most earths, and minerals such as shale, peat and the like, which are oil bearing, contain from small traces to several per cent of iron in combination. The carbon monoxide, CO , generated in the charge, will react with the iron oxide according to the following equation:

In this way the metallic iron is liberated by the carbon monoxide. The hot steam introduced into the charge will immediately react with the metallic iron so produced, according to the following equation:

In this way additional nascent hydrogen is immediately produced and the iron is put back into its oxide condition. Thus the iron may travel back and forth between the carbon monoxide and the steam so as to constantly produce more nascent hydrogen, thereby assisting the action. When the iron content of the charge is very low or entirely wanting, I recommend that iron ore, ferruginous clays or coal ashes be added in small quantity.

This action is also assisted or activated by the presence of a chloride or an acetate salt. This chlorine performs a sort of intermolecular migration by starting the initial reaction and then surrendering its position to oxygen from the steam and then passing on to another molecule for similar action. The iron oxide thus formed is then subjected to the action of carbon monoxide and reduced to a metallic state so that it may be acted upon by the steam to generate the nascent hydrogen.

If desired, the stirring devices such as rabbles may be made of two different metals, for instance, iron and copper, whereby the flow of nascent hydrogen may be increased by electrolytic action at temperatures ranging from 350° to 450° C.

It will be apparent that the generation of nascent hydrogen in direct contact with the material serves a number of beneficial pur-

poses including the conversion of unsaturated hydrogen into saturates, the elimination of sulphur, and the formation of additional quantities of ammonia, the reducing action upon oxidized hydrocarbons such as asphalts and the like. It is also evident that as far as these beneficial advantages are concerned, it is largely immaterial as to just how the nascent hydrogen is generated provided it is nascent in contact with the mass of material undergoing treatment. In this connection, however, it is very desirable to conduct the treatment by hydrogen at temperatures approximating 400° – 500° C., so as to avoid low temperature gas formation, and also to prevent high gas formation or cracking. Inasmuch as nascent hydrogen may be directly generated by the contact of steam and carbon monoxide within this range of temperatures it follows that this particular method of generating the nascent hydrogen is extremely desirable from the standpoint of ability to practice the process with all of the beneficial advantages previously set forth herein.

Normal hydrocarbon oils are said to be of paraffine base, but paraffine base oils when being exposed to weathering conditions absorb atmospheric oxygen and thus become asphaltic base oils. Now, the gas carbon monoxide, CO , has not only the reducing power to deoxidize water vapor (steam) and the iron oxides, but it has the power to extract oxygen from asphaltic oils, when the monoxide gas is in excess of steam. The asphaltic oil, thus deprived of its oxygen is ready for hydrogenation by the nascent hydrogen. By this process asphaltic (slop) oils are rejuvenated and thrown back into the paraffine class whence they originated.

In the drawing, I have illustrated diagrammatically one arrangement of apparatus for practicing the features of the present invention when shale is to be treated. This illustration is purely diagrammatic and is not intended in any sense as a limitation upon the disclosures or practice of the invention.

In this case I have illustrated a main chamber 1 above which is a preliminary heating chamber 2. The material in the chamber 2 may be introduced from time to time into the chamber 1 by manipulation of a door 3 between the two chambers.

The raw material such as oil shale is initially introduced into a feeding chamber 4 by removing the cover 5, and a bell 6 which may be manipulated by a lever 7 is used to control the intermediate delivery of the raw material into the chamber 2.

A gas producer is illustrated diagrammatically at 8, the same delivering the carbon monoxide into the chamber 1 through a pipe 9, the inner end of which is pro-

vided with a number of perforations. The steam may be introduced through a pipe 10 whose inner end is adjacent to that of the pipe 9 and is also perforated.

5 5 A burner 11 serves as a means for heating the chamber 1, and the finally treated residuum material may be withdrawn through a port 12. A connection 13 serves for delivery of the vapors.

10 10 When lime or similar material is to be used in connection with the process, the same may be introduced from a feeding chamber 14 under control of a bell 15 manipulated by a lever 16.

15 15 While I have herein shown and described only a single apparatus for the practice of the features of the present invention, I do no intend to limit myself thereto.

I claim:

20 20 1. The process for the treatment of oil bearing materials for the purpose of saturating with hydrogen their unsaturated hydrocarbons, eliminating sulphur from them, and converting their nitrogen compounds into

25 25 ammonia, which consists in quickly raising the temperature of said oil bearing materials to substantially 450°-500° C. thereby eliminating the formation of fixed or non-condensable gases, thereafter introducing

30 30 carbon monoxide gas and steam independently at temperatures of 450°-500° C. into the mass and bringing them into association at the point of introduction into the mass, to thereby generate nascent hydrogen

35 35 at said temperature in the immediate presence of the mass, together with liberation of carbon dioxide, said nascent hydrogen reacting with sulphur present in the mass to produce hydrogen sulphide, and which

40 40 consists in introducing lime into the mass, whereby the lime reacts with the carbon dioxide and the hydrogen sulphide to produce relatively heavy compounds insoluble in oil, substantially as described.

45 45 2. The process for the treatment of oil bearing materials for the purpose of saturating with hydrogen their unsaturated hydrocarbons, eliminating sulphur from them, and converting their nitrogen compounds

50 50 into ammonia, which consists in instantly raising the temperature of said oil bearing materials to substantially 450°-500° C.

thereby eliminating the formation of fixed or non-condensable gases, thereafter introducing carbon monoxide gas and steam independently at temperatures of 450°-500° C., into the mass and bringing them into association at the point of introduction into the mass, to thereby generate nascent hydrogen at such temperature in the immediate presence of the mass, together with liberation of carbon dioxide, said nascent hydrogen reacting with sulphur present in the mass to produce hydrogen sulphide, substantially as described.

3. The process for the treatment of oil bearing materials for the purpose of saturating with hydrogen their unsaturated hydrocarbons, eliminating sulphur from them, and converting their nitrogen compounds into ammonia, which consists in introducing carbon monoxide gas and steam independently at temperatures of 450°-500° C. into the mass and bringing them into association at the point of introduction into the mass, to thereby generate nascent hydrogen at such temperature in the immediate presence of the mass, together with liberation of carbon dioxide, said nascent hydrogen reacting with sulphur present in the mass to produce hydrogen sulphide, and which consists in introducing lime into the mass, whereby the lime reacts with the carbon dioxide and the hydrogen sulphide to produce relatively heavy compounds insoluble in oil, substantially as described.

4. The process for the treatment of oil bearing materials for the purpose of saturating with hydrogen their unsaturated hydrocarbons, eliminating sulphur from them, and converting their nitrogen compounds into ammonia, which consists in introducing carbon monoxide gas and steam independently at temperatures of 450°-500° C. into the mass and bringing them into association at the point of introduction into the mass, to thereby generate nascent hydrogen at such temperature in the immediate presence of the mass, together with liberation of carbon dioxide, said nascent hydrogen reacting with sulphur present in the mass to produce hydrogen sulphide, substantially as described.

JAMES A. BISHOP
